ELECTRIC SOCKET AND TAP UNIT

Willard G. Tyler, Albany, Calif.

Application September 16, 1950, Serial No. 12,227

Term of patent 14 years

(Cl. D26—1)

To all whom it may concern:

Be it known that I, Willard G. Tyler, a citizen of the United States, residing at Albany, State of California, have invented a new, original, and ornamental Design for an Electric Socket and Tap Unit, of which the following is a specification, reference being had to the accompanying drawings, forming a part hereof, wherein,

Figure 1 is a perspective view of an electric socket and tap unit, showing my new design.

Figure 2 is a plan view of the unit.

Figures 3 and 4 are elevational views of the unit taken from opposite sides thereof.

Figure 5 is an underneath view of the unit.

I claim:

The ornamental design for an electric socket and tap unit, substantially as shown.

WILLARD G. TYLER.
